(57) **CLAIM**

I claim the ornamental design for pliers, as shown and described.

DESCRIPTION

FIG. 1 is a perspective view of the pliers showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is an embodiment, perspective view of my design for the pliers in use. The handles, pivot and arm roots of the pliers are shown in broken lines for illustrative purposes only and form no part of the claimed design.

1 Claim, 6 Drawing Sheets
